(57) **CLAIM**

The ornamental design for a ceiling fan light fixture, as shown and described.

DESCRIPTION

FIG. 1 is a top perspective view of a ceiling fan light fixture showing my new design;

FIG. 2 is a bottom perspective view thereof;

FIG. 3 is front elevational view thereof, the rear elevational view thereof, the left side elevational view thereof, and the right side elevational view thereof being substantially the same thereof;

FIG. 4 is a top plan view thereof; and,

FIG. 5 is a bottom plan view thereof.

The broken line in FIGS. 1 and 4 showing the top opening into the ceiling fan light fixture is included for the purpose of illustrating environmental structure and forms no part of the claimed design.
